UNITED STATES PATENT OFFICE

CHESTER R. SHARAR, OF LOS ANGELES, CALIFORNIA

HYDRAULIC BRAKE

Application filed March 14, 1931. Serial No. 522,613.

This invention relates to improvements in hydraulic brakes.

The principal object of the invention is to provide a brake wherein the braking force is caused by a fluid passing through a restricted opening which opening may be varied in accordance with the driver's wishes.

A further object is to limit the use of friction bands, drums and the like which are easily overheated, squeak and grab.

A still further object is to produce a device which may be attached to any motor vehicle without materially altering the construction of the same.

Other objects and advantages will be apparent during the course of the following description.

In the accompanying drawing forming a part of this specification and in which like numerals are employed to designate like parts throughout the same,

Figure 1 is a diagrammatic illustration of my device as the same would appear when attached to the transmission shaft of a motor vehicle,

Figure 2 is a cross sectional view enlarged, taken on the line 2—2 of Figure 3,

Figure 3 is a cross sectional view taken on the line 3—3 of Figure 2, and

Figure 4 is a fragmentary detail view showing the brake in partial braking position.

Applicant is aware of the fact that efforts have been made to produce hydraulic brakes but these efforts have failed for the reason that the oil would form, heat and therefore would not function the same at all times.

Applicant has produced a very simple device which consists of a casting 5 which is supported upon a motor vehicle in any convenient manner. This casting has the propeller shaft 6 passing therethrough to which propeller shaft is attached a sliding vane 7. This vane is retained in the shaft by a ball 8 which travels in a race 9 and is adapted to seat in the recess 11 when the brake is entirely off. Within the casting 5 is a chamber 12 and slidable within this chamber is a slider 13. This slider is moved within the chamber 12 from the top to the bottom thereof through the medium of a piston 14 traveling

in a cylinder 16, this piston being attached to a connecting rod 17 which is in turn attached to the slider 13.

A valve is shown at 18 which valve is actuated by a control lever 19 for the purpose of transmitting fluid pressure to a point above or below the piston 14. A duct 21 connects the bottom part of the chamber 12 with the top part thereof and acts as a by-pass around the slider 13. The slider 13 has a peculiarly shaped interior chamber 22. This chamber has ports 23 and 24 within which check valves 26 and 27 are positioned. Leading from these check valves are passages 28 and 29, which extend through the slider casting and open at the bottom thereof.

The result of this construction is that when the control rod 19 is moved to operate the valve 18 pressure is admitted so that the piston 14 is moved to its upper limit thus raising the slider 13 to the upper limit, then the oil contained within the casting 5 will be beneath the slider or reservoir A. At this time the shaft 6 will be centrally positioned in the circle described by the ends of the vane 7 when the slider 13 is in its mid-way position; that is when the ball 9 is in the recess 11. In this position the oil within the chamber 22 is merely rotated around and has no restraining effect upon the shaft 6.

Assuming now that it is desired to brake the vehicle to which the device is attached or slow it down partially, the valve 18 is manipulated so that the piston 14 is depressed, the amount of depression controlling the amount of retarding action. As soon as the slider starts to travel downwardly, oil in the chamber A will be transferred through the by-pass 21 to the reservoir B. At the same time if the chamber 22 should be partially empty, oil will be sucked in through the passage 29, pass the check valve 27 and into the chamber 22. The same action will be true of the check valve 26. If the slider moves down as indicated in Figure 4, the oil being pumped around by the sliding vane 7, must pass through the restricted opening between the shaft 6 and the point C. As this distance becomes smaller it is evident that more braking force is being transmitted from the

sliding vane 7 to the shaft 6, and when the slider 13 reaches its bottom position as shown in Figure 2 it will be seen that the point C has come into contact with the shaft 6 and therefore it will be impossible for the sliding vane 7 to pump any more out therebetween and consequently a dead stop results.

It is to be understood that the form of my invention herewith shown and described is to be taken as a preferred example of the same and that various changes relative to the material, size, shape, and arrangement of parts may be resorted to without departing from the spirit of the invention or the scope of the subjoined claim.

Having thus described my invention, I claim:

In a device of the character described, a casting having a chamber formed therein, a piston-like slider positioned within said chamber and engaging the walls of said chamber, whereby when said slider is centrally positioned with respect to said chamber separate chambers will be formed on opposite sides of said slider, a piston secured to said slider whereby said slider may be moved, means for actuating said piston, a rotating shaft extending through said casting and said slider, a sliding vane carried by said shaft, a fluid positioned within said slider and adapted to be acted upon by said vane, a bypass connecting the top and bottom of said chamber whereby fluid in said chamber may be bypassed around said slider, passage ways formed in said slider, said passage-ways communicating with the chamber formed at one end of said slider, valves positioned in said passage ways, and means for maintaining said vane in a fixed position when said slider has been moved a predetermined position with relation to said shaft.

In testimony whereof I affix my signature.

CHESTER R. SHARAR.
